MANUFACTURE OF SHOES

Thomas G. Winnett, Whitman, Mass., assignor
to United Shoe Machinery Corporation, Paterson, N. J., a corporation of New Jersey

Application January 30, 1935, Serial No. 4,130

10 Claims. (Cl. 12—146)

This invention relates to improvements in the manufacture of shoes having uppers provided with flies adapted to be closed by means of lacings or otherwise while the shoes are being worn, and has special reference to the practice of holding the flies temporarily closed to facilitate the lasting of the shoes.

In making a shoe of the type referred to it becomes necessary to close or partially to close the fly either before or after the upper has been placed upon the last and to hold the fly in that condition to retain the upper in shape and in proper position upon the last throughout the various steps of the lasting operation. In the case of a lace shoe it is customary to hold the fly closed during the lasting by temporary fastenings such, for example, as metallic fastening devices or by means of a cord or lace which is threaded through one or more pairs of lacing eyelets and, after being tightened, is knotted to hold it in place. The employment of such fastenings is attended by certain disadvantages however, among which may be mentioned the expense incident to the manufacture and use of the fastenings themselves, or the machines used for applying them, and the time necessarily consumed in their application and removal.

For the purpose of overcoming such disadvantages as those just mentioned, the present invention provides an improvement in the art of shoemaking which involves placing a piece of adhesive tape over the fly of a shoe upper and securing the tape to portions of the upper located at opposite sides of the fly thereby holding the fly temporarily closed to facilitate the lasting of the shoe. Preferably the adhesive tape is coated upon one side only with a pressure energizable and normally non-drying adhesive so that the tape may be caused to adhere to the upper merely by the application of pressure and so that it will function securely to hold the fly closed throughout the various operations incident to the lasting of the shoe, but may nevertheless be readily and quickly removed from the upper at the completion of the lasting operation without damaging the upper or leaving any remnants of the adhesive substance thereon. As illustrated, the fly holding tape is applied to the lining or inner side of the upper so that it will be located between the upper and the last when the upper has been placed on the latter. After the tape has been laid in place it is pressed against the upper with a relatively light pressure sufficient however to hold the fly closed or in a desired normal condition during handling of the upper prior to the lasting of the

shoe, and thereafter the tape is more securely bonded to the upper by the application of additional and more substantial pressure, thereby holding the upper more firmly to resist the stresses to which it is to be subjected in the lasting operation. Advantageously, and as illustrated, this additional pressure is applied simultaneously with the application of heat and pressure to the forepart portion of the upper for the purpose of sticking the doubler or lining to the vamp and performing a preliminary shaping operation upon the vamp prior to the placing of the upper upon the last.

Considered in another aspect, invention is also to be recognized as residing in a novel step product resulting from the practice of my improved method of shoemaking a strip of sheet material temporarily secured by a pressure energizable non-drying adhesive to marginal portions of the inner surface.

The invention will be explained with reference to the accompanying drawing, in which

Fig. 1 is a plan view of the inside of the upper of a lace shoe showing the upper as it appears after the lacing fly has been closed by means of a fly holder consisting of a strip of adhesive tape, and before the upper has been placed upon a last;

Fig. 2 is a plan view of the outside of the upper shown in Fig. 1; and

Fig. 3 is a perspective view of a pressure applying and shaping apparatus illustrating the manner in which the apparatus operates to shape shoe uppers and to complete the application of the adhesive tape fly holder to the upper prior to the lasting operation.

In the drawing the invention has been illustrated in its application to a shoe upper 10 comprising a leather quarter 12, a leather vamp 14, a quarter lining 16, a camp lining 18, and a doubler 20, the doubler carrying adhesive upon its outer side and the several parts having been assembled and stitched together in the usual way. As indicated in Fig. 2, the doubler 20 is composed of woven napped fabric and its napped surface 45 is disposed adjacent to the inner face of the vamp and has on the outer portions of the fibers of the nap minute discrete particles of thermoplastic adhesive. The doubler is held in place by the seam 22 which units the quarter and the vamp 50 but is not at this stage otherwise secured to the vamp. The quarter 12 is formed with a lacing fly 24 at each side of which is located series of eyelets 26 through which a lacing is to be threaded 55 in the finished shoe, and a tongue 28 is secured

at its lower extremity to the quarter in position to underlie the fly and the eyelets.

In accordance with the present invention, as herein illustrated, a piece of adhesive tape 30 is manually laid over the fly 24 of a shoe upper, the fly having been previously closed, or partially closed, as may be desired, and the tape pressed against those portions of the upper which are located at opposite sides of and adjacent to the fly, before the upper is placed upon a last, so as to cause the tape to stick to the upper. As illustrated the tape 30 is applied to the quarter lining 16 at the inside of the upper so that when the upper is later placed upon a last the tape will be located between the upper and the tongue 28. It is to be understood that in closing the fly the adjacent edges of the upper need not necessarily be brought into contact with each other as herein shown, it being in many instances desirable that they be left more or less separated so that the fly is actually only partially closed by the so-called "closing" operation. It should also be understood that instead of applying the tape to a previously closed fly the fly may be closed upon the tape and that the closing of the fly and the application of the tape may, if desired, take place after the upper has been placed upon the last but before the lasting operation takes place.

Preferably the adhesive tape fly holder 30 is coated upon one side only with a pressure energizable, normally non-drying adhesive 32 such, for example, as the adhesive disclosed in United States Letters Patent No. 1,760,820, granted May 27, 1930, upon application of R. G. Drew. Ordinarily only a relatively light pressure will be applied to the tape 30 in laying it, the pressure being sufficient, however, to hold the tape in place upon the upper during handling of the upper prior to the lasting operation, e. g., such handling as that incident to the sticking of the loosely assembled doubler or lining to the vamp and the performance of a preliminary shaping operation on the vamp prior to the placing of the upper on the last. In order, however, to insure that the fly holding tape 30 shall be secured to the upper firmly enough to resist the stresses to which the upper is subjected in the lasting operation it is preferred to apply to the tape, and those portions of the upper upon which it is laid, an additional and substantially heavier pressure sufficient to effect a more secure bonding of the tape to the upper such as will resist the stress of the lasting operation. As herein illustrated, such additional pressure may advantageously be applied by means of apparatus which, in addition to completing the bonding of the tape to the upper, will apply heat and pressure to the vamp for the purpose of sticking the doubler to the vamp and also performing a preliminary shaping operation upon the vamp.

The apparatus herein illustrated as being used for the above purpose is that disclosed in a co-pending application Serial No. 675,375, filed June 12, 1933, in the name of H. L. Sawyer. As illustrated in Fig. 3, such an apparatus comprises a heated inner form or mold 34 and a cooperating outer form or presser member 36, the form 34 having a contoured external upper and outer surface approximately the shape of the portion of the forepart of a shoe last to which the shoe upper will ultimately be lasted and the presser member 36 comprising an outer metallic shell having an inner face complementary to the shape 75 of the form and padded to provide yielding means

for pressing the shoe upper against the form. The presser member 36 may be supported and operated in any convenient manner to press it against the form 34 and release it therefrom, the illustrated member being for that purpose provided with a pair of lugs 38 which are pivoted by pins 40 to a pair of arms 42 which in turn are pivoted to supports 44 on which the forms are mounted. Any convenient means, such as a treadle (not shown), may be provided to swing 10 the arms 42 downwardly to cause the presser member 36 to press the upper upon the form and springs 46 may be provided to maintain the presser member 36 normally in raised position. As shown, two heated forms 34 are provided with 15 cooperating presser members 36 arranged for alternate operation so that one form and its respective presser may remain in operative relation to a shoe upper while a shoe upper is being removed from and another shoe upper is being applied to the other form. The illustrated apparatus, however, differs from that shown in the application above referred to in that the presser members 36, instead of being cut away or notched to avoid applying pressure to the portions of the 20 quarter where the fly is located, are especially shaped to engage and apply pressure to those portions of the quarter.

After the fly holding tape 30 has been applied to the upper, as shown in Fig. 1, and the tongue 30 of the upper has been restored to its normal position, as shown in Fig. 2, the upper is placed upon one of the forms 34 of the pressure applying apparatus above described. The respective presser member 36 is then lowered into position 35 for applying yielding pressure to the upper. The pressure thus applied to the portions of the upper at opposite sides of the fly 24, and to the tape 30 which underlies those portions, causes the tape to become securely bonded to the lining 40 of the upper by means of the adhesive coating on the tape while at the same time the pressure, together with the heat derived from the heated form 34, conforms the vamp to the form while the heat penetrates the lining and the doubler, 45 causing the minute discrete particles of thermoplastic adhesive adhering to the nap of the latter to soften or melt, thereby causing the nap to stick to the inner surface of the vamp. If the doubler has not been previously treated with thermoplastic adhesive a suitable adhesive may be applied between the upper and the doubler, or between the upper and the lining if no doubler is used, just prior to the presentation of the upper to the pressure applying apparatus. In such a case pressure alone may be sufficient not only to complete the bonding of the tape to the upper but also to pre-shape the vamp and to cause the doubler or the lining to adhere to the 50 vamp.

Upon the release of the pressure applied by the presser member 36 the upper is removed from the pressure applying apparatus and is placed upon a last having an insole thereon after which the usual lasting operation is performed in the course of which the overlasted margins of the upper are secured to the insole.

Either before or after the outsole has been applied (according to the particular process which is employed for attaching the outsole) the last must be removed, and before attempting to remove the last it is preferable to break the bond between the upper and the strip of fly holding tape and to open the fly to relieve the tension 70 75

upon the upper. On account of the fact that the adhesive coating upon the fly holding tape is normally non-drying, the tape may be removed by pulling or peeling the portions of the upper at opposite sides of the fly from the tape. Moreover, because of the character of the adhesive employed, it will be found that the inner surface of the upper which was engaged by the adhesive has not been injured in any way by the sticking of the tape thereto or its removal therefrom and, further, that no trace of the adhesive remains upon the upper. The tape may be discarded either before or after the last has been pulled.

15 Having described my invention, what I claim as new and desire to secure by Letters Patent of the United States is:

1. That improvement in methods of making shoes having uppers provided with flies which 20 consists in placing a piece of adhesive tape over the fly of a shoe upper with the adhesive side of the tape overlying portions of the upper at opposite sides of the fly, and subjecting the upper and the tape to pressure between cooperating 25 forms thereby performing a preliminary shaping operation upon the upper and at the same time causing the tape to stick securely to the upper.

2. That improvement in methods of making 30 shoes which consists in closing the fly of a shoe upper assembly comprising an upper and a lining member carrying adhesive, placing a strip of adhesive tape over portions of the upper at opposite sides of the fly, and by the application of 35 pressure simultaneously bonding said lining member and said tape securely to said upper.

3. That improvement in methods of making 40 shoes having uppers provided with flies which consists in sticking a strip of adhesive tape to the inner side of the portions of a shoe upper at opposite sides of the fly thereby holding the fly temporarily closed, lasting the upper, and subsequently opening the fly to facilitate removal 45 of the last by pulling said portions of the upper away from said tape.

4. That improvement in methods of making 50 shoes which consists in closing the fly of a shoe upper, laying a strip of adhesive tape with relatively light pressure upon those portions of the upper at opposite sides of the fly to hold the fly closed during handling of the upper prior to the 55 lasting of the shoe, later applying more substantial pressure to the tape and the upper and thereby securing them together more firmly to resist the stresses to which the upper is to be subjected in the lasting operation, lasting the shoe, and thereafter removing the tape from the upper.

5. That improvement in methods of making 60 shoes of the type in which the upper is provided with a fly and a tongue which consists in closing the portions of the upper at opposite sides of the fly upon a strip of adhesive tape located between the upper and the tongue, and thereaft-

er applying heat and pressure to the upper for the purpose of pre-shaping the latter while at the same time pressing the upper against said tape to facilitate the bonding of the tape to the upper.

6. That improvement in methods of making 10 shoes having uppers provided with flies which consists in placing a piece of adhesive tape over the fly in the quarter of a shoe upper, pressing the tape lightly against portions of the upper located at opposite sides of the fly thereby sticking the tape to those portions of the upper and holding them in a predetermined relation to each other to facilitate the lasting of the shoe, 15 and thereafter placing the upper upon a form and applying heat and pressure to the upper to pre-shape the latter while simultaneously pressing the upper and said tape together with a relatively heavy pressure thereby insuring the establishment of a more secure bond between them. 20

7. That improvement in the art of shoemaking 25 which consists in closing the fly of a shoe upper, laying a strip of adhesive tape with relatively light pressure upon those portions of the upper at opposite sides of the fly to hold the fly closed during handling of the upper prior to the lasting of the shoe, subsequently applying more substantial pressure to the tape and the upper thereby securing them together more firmly to 30 resist the stresses to which the upper is to be subjected in the lasting operation, placing the upper upon a last, lasting the shoe, and thereafter, but before removing the last from the shoe, peeling the portions of the upper at opposite 35 sides of the fly from said tape thereby opening the fly and relieving the tension on the upper to facilitate the removal of the last.

8. A step product consisting of a shoe upper 40 having a fly and a tongue, said fly being held closed by means of a piece of tape interposed between the tongue and the upper, said tape having its outer surface secured by means of adhesive to the marginal portions of the inside of the upper at opposite sides of the fly and said tape 45 being so disposed that its inner surface will lie against said tongue when the upper is on a last.

9. A step product consisting of a shoe upper 50 assembly comprising an upper and a lining, said assembly having a fly held closed by a strip of sheet material temporarily secured by a pressure energizable non-drying adhesive to marginal portions of the inner surface of the lining at opposite sides of the fly.

10. That improvement in methods of making 55 shoes which consists in closing the fly of a shoe upper assembly comprising an upper and a lining member carrying thermoplastic adhesive, placing a strip of adhesive tape over portions of the upper at opposite sides of the fly, and by the application of heat and pressure simultaneously bonding said lining member and said tape 60 securely to said upper.

THOMAS G. WINNETT.

CERTIFICATE OF CORRECTION.

Patent No. 2,071,775.

February 23, 1937.

THOMAS G. WINNETT.

It is hereby certified that error appears in the printed specification of the above numbered patent requiring correction as follows: Page 1, second column, line 17, beginning with the words "a strip" strike out all to and including "surface" in line 20; line 40, for camp" read vamp; and that the said Letters Patent should be read with these corrections therein that the same may conform to the record of the case in the Patent Office.

Signed and sealed this 30th day of March, A. D. 1937.

(Seal)

Henry Van Arsdale
Acting Commissioner of Patents.
